UNITED STATES PATENT OFFICE.

FRANK F. NOVAK, OF NEW YORK, N. Y.

ACETYLENE-GAS GENERATOR.

1,162,708.

Specification of Letters Patent. Patented Nov. 30, 1915.

Application filed March 11, 1913. Serial No. 753,614.

To all whom it may concern:

Be it known that I, FRANK F. NOVAK, a citizen of the United States, and a resident of New York, county and State of the same name, have invented certain new and useful Improvements in Acetylene-Gas Generators, of which the following is a specification.

This invention relates to acetylene gas generators and particularly to that class in which the gas is generated by the action of water upon calcium carbide in any desired quantity within the capacity of the apparatus.

The objects are to provide means for positive automatic control therein so as to avoid extremes either of excessive or insufficient production of gas. To combine with the apparatus means for washing and purifying the gas, means to prevent clogging of the apparatus and its various appurtenances, and means for replenishing the carbide without ceasing the operation of gas making, it being practical to recharge the same if need be at night without artificial light. And finally, to provide a gas apparatus of simple construction, easily charged, absolutely automatic, certain and safe in its action. Its objects are attained by the novel construction and arrangement of parts hereinafter fully described and shown in the accompanying drawings in which:—

Figure 1 is a front elevation in perspective of the entire apparatus as installed for operation. Fig. 2 is a partial side elevation of the same, parts being broken away exposing the interior. Fig. 3 is a partial plan and sectional view taken on a line immediately above the gas tank shell. Fig. 4 is a sectional view taken on line 4—4 of Fig. 3, showing the interior construction. Fig. 5 is a sectional view through the condenser taken on line 5—5 of Fig. 3. Fig. 6 is a perspective detail illustrating the positive means of water control. Fig. 7 is a perspective view of the trays used in the carbide holding chambers. Fig. 8 is a perspective view of the carbide chamber closures. Fig. 9 is a perspective view of the carbide holding chambers. Fig. 10 is a perspective view showing the water supply controlling means, and Fig. 11 is a similar view of a modified means for the same purpose.

The device consists essentially of a gas tank 20 resting upon a base 21, the tank

being cylindrical in shape while the base is 55 preferably made rectangular and adapted to rest upon any suitable foundation.

Within the gas tank is a loosely fitted gas bell 22 adapted to move freely up and down therein being guided by brackets 23, provided with ball bearings at 23' so as to avoid friction which might cause fluctuations in gas pressure, the same being secured at opposite sides of the dome-shaped top 24, and slidable upon the guides 26 arranged on 60 the outside of the gas tank 20 at its top; these guides are connected by a cross bar 27 acting as a brace between the guides which are provided with collars 28 acting as stops against which the brackets 23 may 65 contact at the extreme limit of upward motion of the gas bell 22.

Upon one side of the gas tank 20 near the top and connecting therewith is an open rectangular supply tank or vessel 30 in 75 which is a float valve 31 regulated by the lever 32 connected with the hollow float 33 so that when the water rises to a predetermined level it shall be cut off. An overflow pipe 34 is provided to carry away any excess of water, the same leading to the sewer or other point of disposal.

The tank 30 is fed by the pipe 35 leading from any convenient source as a water supply system or a reservoir provided for the 85 purpose.

It is to be understood that the tank 30 is open to its full height to the water space between the gas tank 20 and the gas bell 22 so that any water in the tank is freely 90 discharged into the space.

In order to maintain a constant level when the apparatus is working normally, the float operates the valve as before described, but if the bell descends within the gas tank for 95 any cause, to a landing position in consequence of an unsufficient supply of gas, the water supply is completely shut off by the following means:—Secured on top of the dome 24 is a hook-shaped member 38 downturned for engaging with the loop 39 of a metal tape 40, or its equivalent, the lower end of which engages with the float valve lever 32, the tape or band passing between pulleys 41 mounted on a bracket 42 supported at the edge of the gas tank. It will 100 be understood that this last mentioned device becomes operative only when the gas

bell drops below its normal working level as ordinarily the hook 38 is above and out of contact with the loop 39 although the latter is always held in a receptive or engagable position by means of a stop 43 secured to the metal tape 40 in front of the pulleys 41. This arrangement is designed to avoid friction or load on the gas bell when working under normal conditions, 5 10 which has been an object throughout so as to render the apparatus as free from fluctuations in pressure as possible, otherwise the hook might be directly connected to the tape.

A siphon in the form of a bent tube is 15 disposed over the edge of the gas tank 20, the interior member 35 being upturned near its end 46 and provided with a finely meshed metal net or sieve 47 preferably globular or convex, the same preventing any undesirable 20 matter from entering the pipe which is operatively connected to the gas bell 22. The location of the siphon intake 47 with respect to the top of the gas tank 20 is such that should the bell, to which the siphon is 25 attached, rise abnormally, the intake will be brought above the water seal, completely cutting off the water supply to the carbide and hence cause the machine to cease making gas.

30 At the highest point of the siphon in the bend connecting the members 45 and 48, is a pipe 160 having a cock 161 controlling the passage between the filling or charging nozzle 162 and the interior of the siphon 35 providing convenient means for starting the same into operation after any period of rest. The outer member 48 extends downwardly alongside the tank 20 and has a bend at its lower end 49 to which is connected by 40 a spring hinge, 50, a curved member 51, its opposite end being normally disposed between the front and rear walls of the drain box 52 attached to the tank 20. This drain box 52 is open at the top 53 and also along 45 the side 54 adjacent to the siphon except for a short distance above its lower, rounded end, the closed portion forming a cup 55 whose edge acts as an abutment 56 so that when the siphon and bell are moved down, 50 relative to the gas tank and drain box, the curved tubular member 51 is caused to pivot upon the hinge 50 opening the joint in the normally communicating passage between it and the other members 48 and 49 of the 55 siphon, allowing any water which may be contained therein to flow out and effectually cutting off the further passage of water therethrough until the siphon has been raised bodily with reference to the drain 60 box 52 and the spring hinge 50 has acted to restore the parts to normal condition; this arrangement is best shown in Fig. 11, while the modification indicated in Fig. 10 provides other means to prevent the egress of 65 water from the part 51' to within the cup

55'; these means consist of a horizontal shelf 57 supported by a vertical member 58, the same being adjustably connected to the rear portion of the drain box and out of the path of travel of the siphon tube 51'. 70

Upon the shelf is rigidly secured a cylinder 60 having an open ring-like cover 61 removably engaged at the top adapted to make contact with the rubber washer 62 normally pressed upwardly against it by means of the spring 63 within the cylinder; if now the bell and siphon descend, the flat horizontally disposed end of the tube 51' will squarely contact with the washer 62 thereby preventing the passage of water, but 80 because of the flexibility of the spring 63 the siphon may continue to descend for some distance farther during which time the passage remains closed.

It is to be understood that either form of 85 these water passage controlling means may be used as precautionary safe-guards operable only when the gas tank is devoid of gas or so nearly in that condition as to require attention. 90

The lower end of the drain box 52 is recessed downwardly forming a cup 55 and is provided with a swivel cock 65 the spout 66 of which is capable of being turned so that the stream passing therefrom may enter into 95 either of the several compartments in the tray 67' immediately below, they being arranged in a circular arc. The partitions 68' between the compartments in the tray 67' are formed with a series of openings 69' so 100 that if the water is permitted to rise in the compartment to the height of the openings it will flow from one to the next adjoining. In Fig. 11 a similar swivel cock 65 is used to drain the cup 55, the spout 66 being provided with a telescopically sliding member 66'; this is done so as to enable the discharge to enter any of the compartments formed by the partitions 68 in the tray 67 which in this case is made rectangular and 105 not curved as before described; openings 69 are similarly formed through the walls of the partitions for the automatic transmission of water from one compartment to another when the first acquires an excessive quantity. 110 Each of the several compartments have individual pipes 70 extending downward and arranged to discharge into its corresponding carbide chamber 72. 115

If for any cause the water should exceed 120 the quantity capable of being held in any one of the carbide chambers, it will back up in the pipe leading from its corresponding compartment in the tray 67 or 67' and from there be led to the next adjacent compartment. Enough however would remain in that compartment so that it could be detected by the insertion of an operator's finger showing that the carbide in that particular chamber had become exhausted or that for some 125 130

reason was inoperative. In this case, the swivel cock 65 is turned to the next compartment whereupon the exhausted carbid chamber may be examined and re-charged.

5 The carbid chambers 72, three of which are shown in the present embodiment, each contain a rectangular metal box-like receptacle 73 made in the form of a drawer open at the top and provided with a plurality of transverse partitions 74 form compartments 75, each compartment being adapted to hold a certain amount of carbid; water entering the first compartment from the pipe 70 causes gas to form continuously until the 10 carbid is exhausted; when the water has reached the level of the openings 76 formed in the side wall it will set up the same action in the next compartment and so continue until all of the carbid in the several compartments has become exhausted which will take 15 place in one after the other as the water rises to the various levels of the openings 76; each carbid receptacle is provided with a swinging drawer pull or operating handle 20 25 77 for convenience in handling.

Over all the compartments except the first, in each carbid receptacle, which should be charged half full only, is a plate 78 acting as a cover and preventing the carbid from 30 rising beyond the top edges and clogging the gas conveying means, which it might do by reason of swiveling when saturated; in each compartment in the carbid receptacles is placed a thin metal tray 80 having sides 81 35 loosely fitting within the compartments; these side members are provided with a lifting bail 82, which also acts as a brace between them, and has a loop 83 formed centrally therein in which a bent rod 84 may be inserted 40 when raising the plate; also in the bottom plate are holes 85 in which other rods or the like may be inserted when dumping the contents, that is the gas exhausted carbid, the trays being provided for holding the carbid 45 in such manner as to be conveniently operated without soiling the operator and for emptying the receptacle expeditiously and in a cleanly manner.

The covers 88 of the carbid chambers 72 50 are provided with gaskets 89 so that they may be sealed hermetically; the covers are further provided with lugs 90 formed integral at the top and bottom respectively; these lugs serve to guide a clamp-bar 91 55 having forks 92 with in-turned prongs 93 extending alongside the lugs and engaging with flanged projections 96 extending outwardly from the base 21; a hand operable set screw 95 is provided in the bar 91 for 60 drawing the covers tightly into position and an integral handle 97 is formed with the cover plate 88 for convenience in operating the same.

On the inner surface of the gasket 89 and 65 secured to hold it in position is a sheet metal

plate 98 having an inwardly turned flange 99 adapted to enter the open end of the carbid chamber, centering and properly locating the cover 88 in correct position for clamping, thus avoiding any difficulty and enabling the 70 operation to be performed by the sense of touch alone.

The foregoing arrangement provides means for accurately centering the clamp and cover by the sense of touch alone so 75 that the operation can be performed even in the dark and without danger of misplacement of parts.

Each chamber is independent so that one may be charged singly or more as may be 80 desired; thus it will be obvious that gas making may continue uninterruptedly even if one chamber be withdrawn.

Returning to the tank 30, before described, when the float is depressed, as at 85 the initial operation, water enters the gas tank 20 and will continue to do so until the float rises. The siphon being charged begins to act automatically discharging water through the cup 55 and swivel cock 65 into 90 any of the compartments in the tray 67, from whence it is delivered to the carbid chambers 72 through the pipes 70 formed into traps at their lower ends and entering the charged receptacle 73, starts the formation 95 of gas. To each of the chambers 72 are connected discharge pipes 100 the same extending up through the base into the tank 20 just below the normal water level at which point they are connected by fittings 100' to short cross members in turn having fittings 101' from which the pipes 101 extend downward into the washing chamber 102 nearly to its bottom; thus the gas is cooled by 105 its passage through the pipes 100 enveloped in the water; the fittings 100' and 101' are provided with removable closures in their openings opposite the pipe entrances thereby affording ready means for cleaning out the pipes without removal. 110

The washing chamber 102 may be of any approved form, preferably cylindrical as shown, and rests within the gas tank over the carbid chambers; it is made water-tight, being provided with a cover 103 through 115 which the several pipes 100 enter. Means for maintaining a supply of water therein are provided by the inlet pipe 104, the same extending out through the tank 20 where it is upturned as at 105 and furnished with 120 an enlarged filling nozzle 106 readily accessible for convenience in pouring in water as from a bucket.

Besides washing the gas and freeing it of 125 impurities the water in the washing chamber 102 acts as a seal effectually preventing the return into the pipes of gas discharged into the chamber.

An outlet or drain pipe 107 extends from the opposite side of the washing chamber 130

outwardly through the tank and is provided with a cock 108 so that the contents of the chamber may be drained as often as may be required, and replenished by the inlet 5 nozzle 106 or both working in conjunction as they must be when the apparatus is making gas; this arrangement gives a thorough passage effectually cleaning out any sediment.

10 The gas entering the washing chamber 102 from the pipes 100 rises up through the water therein, which retains the ammonia, and enters the pipe 110 passing through the cover 103 and extending up within the tank 15 20 to a point above the water level where the washed gas is discharged within the bell 24 which collects the same and whose vertical movement is caused by the fluctuations of the quantity contained, the same being 20 variable through the process of making and the amount withdrawn.

From the bell 21 the gas is taken through the pipe 112, the upper end of which extends above the water level, the lower entering 25 a condensation chamber 115 located in the base at the rear of the carbide chambers and having a flanged open portion extending out beyond the base casing; a plate cover 116 and gasket 117 are provided for this 30 opening adapted to be rigidly secured by appropriate bolts and nuts 118; this opening permits of ready accessibility to the interior of the condensation chamber in order 35 to make connections, repairs and the like therein. This condensation chamber 115 is made tight to hold a quantity of water acting as a seal to the inlet 112, the same having a member extending below the water surface and also a discharge pipe 120 extending laterally outward beyond the base; the chamber is further supplied with a safety or blow off pipe 121 in case of an 40 excessive pressure; also through the cover is a pipe 122 extending up into the gas bell 45 cap 25, which latter has a depending cylindrical member 123 acting in conjunction with the pipe 122 as a safety device to prevent raising the bell to an undesirable height; means for supplying water to the 50 condensation box are provided by the pipe 124 having the open nozzle 125 arranged exteriorly of the base.

The foregoing elements constitute the gas making apparatus and it now remains to 55 describe the purifying means used in connection, which consist of cylindrical tank 130 mounted on a base 131 resting upon any suitable foundation and provided with openings 135 for ventilation extending through 60 its walls. The tank 130 has head 133 secured by bolts 134 and tight bottom 135 similarly fastened to flanges formed integral with the tank at each end; within the tank are disposed a plurality of circular perforated plates 136 having rigid upstanding

handles or bail members 137 upon which the next succeeding plate may rest, the last of the series having its handle just below the head 133.

The pipe 120 enters a cock 140 having an 70 operating stem 141, provided with a hand lever 142 and passing through a guide 143 attached to the tank 130 is continued upward to a point just above the tank head 133, where it is turned and formed to suit 75 a circular plate 145 to which it is rigidly secured in such manner as to render it impossible to get at the bolts 134 when the cock is open, but when the cock is closed, by 80 turning the stem 141 the cover plate is swung to one side thereby giving free access to the bolts so that the head 133 may be removed, the plates 136 withdrawn and the purifying material disposed thereon renewed. From the cock 140 is a pipe 147 85 passing through one of the openings in the base 131 where it is joined to a vertical pipe 148 extending up through the bottom plate 135 nearly to the head 133 passing 90 through the perforate plates 136 and discharging gas at its open top. The discharged gas is now forced by the pressure of the gas bell to pass down through purifying and filtering material disposed on the 95 perforated plates and eventually out through the service pipe 150 to wherever it may be required.

Having thus described my invention and ascertained its operation, purpose and use, what I claim as new and desire to secure 100 by Letters Patent, is:

1. In an acetylene gas generator, the combination with a water tank and an inverted gas bell movable thereon, of a supply tank having an open passage to said water tank, 105 a supply pipe thereto having a valve controlling the passage therethrough, a lever operating the valve, said lever having a float normally controlled by the height of water in said tank and a member attached 110 to said bell engageable with said lever whereby the water supply is closed when said bell descends below a fixed limit.

2. In a gas generator, the combination with a water tank and a gas bell movable 115 thereon, of an auxiliary tank connected therewith by an open passage, a supply pipe thereto, a valve controlling said supply pipe, a buoyant float combined with said valve adapted to operate relative to a predetermined water level and means combined with said gas bell for positively closing said valve irrespective of the float, said means being operative only when said gas bell passes below a predetermined limit.

3. In a gas generator, the combination with a gasometer having a water seal and a gas bell movable therein, of means for normally maintaining a substantially fixed water level in said gasometer, and means com- 130

bined with said gas bell for independently closing the water supply thereto, when the gas is exhausted below a definite amount.

4. In an acetylene gas generator, the combination with a gasometer, having a water seal and carbid chambers, of a tray arranged on said gasometer, partitions formed in said tray, corresponding to said carbid chambers, said partitions being perforated adjacent to their lower edges, pipes communicating between the compartments formed by the partition and their corresponding carbid chambers, an open vessel above said tray having water connections with the water seal, means 10 for breaking said water connections, said

means becoming operable upon an abnormal accumulation of gas, other means for breaking said water connections operative by a deficiency in the supply of gas, and an extensible swivel cock in said vessel adapted 20 to discharge between any of said partitions in said tray whereby water may be delivered to any of said carbid chambers.

In testimony whereof I have signed my name to this specification in the presence of 25 two subscribing witnesses:

FRANK F. NOVAK.
